APPAREL

Marius Caridis, Los Angeles, Calif.

Application September 25, 1934, Serial No. 745,474

5 Claims. (Cl. 2—115)

This invention relates to the class of apparel, and is more particularly directed to an improvement upon the form of invention disclosed in my co-pending application Serial No. 667,654, filed April 24, 1933, of which the present application is a continuation in part.

An object is to provide an improved form of shirt wherein means are provided for conveniently and effectively securing same to the waist band of trousers in a manner to exert a downward pull upon the shirt and thereby cause the shirt to more perfectly conform to the contour of the shoulders of the wearer and to be held taut between the shoulders and the waist line, so as to prevent overfullness thereof, which, if not avoided, causes the bosom to pucker and appear untidy or not neat and dressy.

Another object is to provide means which is entirely constructed of the same material as the shirt and which may be devoid of structural features that would prevent its being laundered with the shirt.

A still further object is to provide a device for the purpose stated which will in no way detract from the intended good appearance of the shirt and which, when attached to the waist band of trousers, will hold the lower part of the shirt from working out of the trousers.

A still further object is to provide an attachment of the kind and for the purpose stated which can be incorporated in the shirt without materially adding to the manufacturing cost thereof.

Another object is to provide means which can be adjusted to a position where it can be wholly concealed beneath the shirt, at the pleasure of the wearer.

My invention comprehends other features of construction which, together with those specified, are fully described hereinafter and specifically recited in the claims.

My invention will be better understood by reference to the accompanying drawing, in which

Figure 1 is a view in front elevation of one form of my invention, the attaching devices being shown in their inactive positions of adjustment;

Figure 2 is a view similar to Figure 1, showing the attaching devices attached to a waist-line garment;

Figures 3 and 4 are sections taken, respectively, on the lines 3—3 and 4—4 of Figures 1 and 2;

Figure 5 is a perspective view of one of the attaching devices;

Figure 6 is a front view of a portion of a

shirt showing a slightly different form of the invention;

Figure 7 is a section on line 7—7 of Figure 6.

I shall have it clearly understood that the invention proposes the use of means which is primarily, if not entirely, designed for the purpose of adapting the shoulder and neck portions of the garment to the shoulders of the wearer and to exert sufficient pull in a downward direction on the garment to give thereto a more dressy appearance than was heretofore present. I make no claim to the construction of the shirt per se or apart from the attaching devices which I have designed to fulfill the specific purpose herein referred to.

While my invention can be used in connection with shirts not provided with what are known as patch pockets, it will be illustrated in the accompanying drawing as employed in combination with shirts having such pockets.

The shirt 10 is provided with identical pockets 11—11 each including a single ply of textile material 12 sewed to the front of the shirt in the usual manner and, as illustrated, each pocket is provided with a closure 13 which may be secured in a closed position by the button 14 on said ply 12.

Between the lower edge of the pocket material and the material of the shirt proper, and stitched to both said materials, is one end of a flexible flat tape 14a, preferably of inelastic soft material. By inelastic material I mean material which is devoid of rubber and of a kind either the same or nearly like that of the shirt. If desired, however, garter elastic may be used, and by this I mean material which in part is formed of rubber and, therefore, can be stretched. The tape 14a

for each said pocket is constructed of a single strip of fabric folded to provide two parallel leads 15—15, whose inner edges are tacked at 40 suitable intervals as at 16 to provide a longitudinal series of button holes 17. At the lower end of the tape, the two leads 15—15 are folded on themselves and the plies at this point stitched together at 18. The length of each tape 14a is 45 approximately co-extensive with the depth of the pocket with which it is associated and when folded to the position shown in Figure 1, it may be extended linearly of the front of the pocket and its free end fastened to the button 14 with which latter the flap 13 can also be fastened. When the tape is adjusted to the position shown in Figure 2, however, the free end thereof can be passed in back of the waist band of the trousers and attached to one of the customary trousers 50

buttons 19. In view of the provision of a vertical or longitudinal series of button holes 17 in the tape, it follows that a desired one thereof can be attached to the button 19, depending upon the 5 degree of tautness to be given the shirt. When two such tapes are employed at the front of the shirt, as herein disclosed, the shirt can be uniformly pulled in a downward direction so that both shoulder portions of the shirt, as well as 10 the neck portion thereof, will more perfectly fit the form of the wearer at the shoulders and neck, and the front of the shirt from a point at the waist line of the trousers to the neck of the shirt maintained in a neat and dressy condition, 15 there being less tendency of the shirt to pucker and wrinkle than before, or in instances where no such tapes are employed.

By attaching the tapes to the pockets as herein described, it follows that the pocket materials 20 and the material of the shirt proper function to reinforce the tapes at the places where they are sewed to the shirt, whereby to prevent accidental tearing of the shirt when pull is applied to said tapes in the ordinary use thereof.

25 In Figures 6 and 7, the pocket of the shirt can be formed as usual and directly beneath same and formed in the material of the shirt proper is a button hole 20. The tape 14a is the same as the one previously referred to, and when not in use it can be passed or threaded through the button hole 20 where it will be wholly concealed by the material of the shirt as clearly indicated in these figures. The construction is otherwise the same as the form first above described. When it 30 is desired to use the tape, it is merely required that it be retracted or withdrawn from the opening 20 and exposed exteriorly of the shirt and then connected to the trousers in the manner stated first.

40 For the purpose of the hereto appended claims, the material of the shirt, the material of the pocket 11 and the material of the tape 14a will be called plies of material, the same secured together so that the major part of the tape material will be free and adapted to extend downwardly for 45 attachment to the trousers. I am thereby able to use the pocket material as a reinforcing means at the place where one end of the tape attaches (is stitched) to the shirt, thus preventing the 50 material of the shirt from being torn when pull is applied to the tape.

It is to be understood that the primary purpose 55 of the invention is to provide effective means for causing pull to be applied to the shirt to thus maintain same in a neat and attractive condition. It is not proposed that it shall function to hold up the trousers or to replace the usual 60 waistline belt. In fact, to the end that the device may function to satisfy the ends in view and to prevent possible tearing of the shirt, it is intended that the usual form of belt 21 be employed or that the use of suspenders be resorted to.

What is claimed is:

65 1. A shirt having horizontally alined pockets in its bosom portion, and means for exerting a downward pull upon the shirt when the lower portion of the latter is placed within the waistband of trousers, said means comprising tapes

complementary to the respective pockets and each having an end stitched to the material of the pocket at the bottom thereof and to the material of the shirt and having a free portion of a length to extend into the waist band of the trousers and formed for attachment to a suspenders button at said waist-band.

2. A shirt having horizontal alined pockets in its bosom portion, and means for exerting a downward pull upon the shirt when the lower portion 10 of the latter is placed within the waist-band of trousers, said means comprising tapes complementary to the respective pockets and each having an end stitched to the material of the pocket at the bottom thereof and to the material 15 of the shirt and having a free portion of a length to extend into the waist band of the trousers and formed for attachment to a suspenders button at said waistband, the material of the shirt having a hole formed therein beneath each pocket and 20 the tape which is complementary to the pocket being adapted to be passed through the opening from a point interiorly of the shirt to a point exteriorly thereof or vice versa.

25 3. The combination with a shirt having horizontally alined patch pockets and the material of the shirt having holes beneath the bottoms of the pockets; of means for exerting a downward pull upon the shirt from points approximately at said holes and for securing the lower part 30 of the shirt confined within the waist band of a nether garment and comprising a tape depending from each pocket and threaded through the opening beneath the pocket to be concealed beneath the material of the shirt and adapted to be withdrawn from said opening and disposed in a depending position from the pocket in front of material of the shirt and provided with a free lower extremity formed for attachment to the waistband of said nether garment.

40 4. A shirt, the bosom of which is provided with pockets, the front wall of each pocket having a button secured thereto at the top thereof, a vertically foldable strap secured at one end beneath each pocket and having a length to extend from the bottom of the pocket to the waist line when folded to one possible position and having a button hole for attachment to a button at the waistband of a nether garment and said buttonhole adapted when the strap is folded to another possible position to receive the button at the top of the pocket so that the strap will be disposed wholly at the front of the pocket.

45 5. The combination with a shirt having a patch pocket of the type provided with a closure flap having a buttonhole and the front of the pocket having a button to pass through the buttonhole to secure the flap in closed position, of a strap secured at an end to the shirt at the bottom of the pocket and having a buttonhole at its opposite end, the strap being foldable vertically from a position at the front of the pocket to a position terminating at the waist line of the shirt and the buttonhole of the strap adapted when the strap is in the first position to receive the button 60 of the pocket and adapted when in the second position to receive a button at the waist line of a nether garment.

MARIUS CARIDIS.
